Patented Aug. 26, 1919.

Inventor:

Henry H. B. Graham

by Edward R. Alexander

his Attorney

UNITED STATES PATENT OFFICE.

HENRY W. B. GRAHAM, OF NEW LONDON, OHIO; MARGARET GRAHAM EXECUTRIX OF SAID HENRY W. B. GRAHAM, DECEASED; SAID INVENTOR ASSIGNOR TO THE ARNOLD-CREAGER COMPANY, OF NEW LONDON, OHIO A CORPORATION OF OHIO.

BRICK-MOLD.

1,314,057.

Specification of Letters Patent. Patented Aug. 26, 1919.

Original application filed March 1, 1916, Serial No. 81,425. Divided and this application filed October 27, 1916. Serial No. 127,981.

To all whom it may concern:

Be it known that I, HENRY W. B. GRAHAM, a citizen of the United States, residing at New London, in the county of Huron and 5 State of Ohio, have invented certain new and useful Improvements in and Relating to Brick-Molds, of which the following is a specification.

This invention relates to molds for making bricks, particularly molds of the multiple sectional type adapted to be automatically moved to and from the filling position below the die of a brick making apparatus.

15 One object of the invention is to provide an improved brick mold so constructed that its upper edges will at all points engage with the die when moved to a position therebelow, whereby said die will scrape off the surplus 20 brick material as the mold is moved forwardly.

A further object of the invention is to provide a brick mold having improved end members adapted to engage with various 25 parts and supporting members of the brick making apparatus as the mold moves, gravitates or is otherwise conveyed through the apparatus.

With these and other objects in view, the 30 invention consists of the parts or combinations of parts hereinafter described and set forth in the appended claims.

This application is a division of my application Ser. No. 81,425 filed March 1, 1916.

35 For the purpose of illustration, I have, in the accompanying drawings shown and herein described one form of device embodying my invention.

In the drawings:

40 Figure 1 is a top plan view of a mold embodying my invention.

Fig. 2 is a side view of the mold, partly in section on the line 2-2 of Fig. 1. Fig. 2a is a fragmentary side elevation, enlarged, 45 of the mold.

Fig. 3 is a transverse section on the line 3-3 of Figs. 1 and 2.

Fig. 4 is a detail view.

Fig. 5 is a fragmentary transverse sectional view of a brick making apparatus 50 showing a mold in position below the die.

Fig. 6 is a fragmentary top plan view of

the brick making apparatus showing certain parts thereof which engage with the end members of the mold to operate, support and 55 guide the latter.

In the drawings, 14 indicates as an entirety the mold, adapted to move, gravitate or be conveyed through the brick making apparatus indicated as an entirety at 1 in Figs. 60 5 and 6. In Fig. 5, 7^b indicates the front plate or wall of a charging chamber. 14^a indicates side members to which is secured a front plate 7^b. 13 indicates the die through which the material is forced by a 65 press platen (not shown). The lower surface of the die is spaced from and arranged parallel to the table or base 22 of the apparatus. The die 13 engages with the upper surface of the mold 14 when the latter 70 is pushed forward over the mold table or base 22 to a position below the die. The base 22 is so supported by suitable devices, indicated as an entirety at 28, relative to the lower edge of the die 13, that a space, approximately equal to the height of the mold, 75 14, is left between the base and die 13. In operating the apparatus 1, the molds are successively moved to a position below the die 13 for filling and then forwardly, preferably, to bumping, dumping and receiving mechanisms, which are indicated in Fig. 6 at 24, 25 and 52, respectively, and sanding apparatus (not shown).

Of the mold, 14^a indicates a pair of side 85 members. 14^a indicates a pair of end members, each preferably connected in a well known manner to adjacent ends of the side members 14^a. 14^c indicates a plurality of partitions connected at their opposite ends 90 to the side members 14^a. The partitions 14^c are preferably of the same width or height as the side members 14^a. The partitions 14^c are uniformly spaced from each other and from the inner side walls of the end members 14^a, to divide the mold into a plurality of sections 14^c, each of which forms a brick mold.

14^d indicates a plurality of bottoms, one for each mold section 14^c, fixed to the side 100 members 14^a in any desired manner. The bottoms 14^d are preferably spaced from each other a distance slightly greater than the thickness of each partition 14^c. This

form of construction is for the purpose of providing vents or openings 14^a in the bottoms of the mold sections 14^c along either edge of the bottom and the adjacent wall or edge of the adjoining partition. When the mold sections are being filled, the air therein is forced out through these vents; on the other hand, when the mold 14 is dumped, air has access to the under sides 10 of the bricks to prevent a vacuum.

The end members 14^b extend laterally from the opposite ends of the molds and preferably comprise solid blocks of rectangular shape in cross section. The blocks 15 14^b are of a size to provide relatively wide upper and lower flat surfaces which serve as shoes on which the mold 14 runs or slides on the various supporting, guiding and conveying parts of the apparatus 1 as it moves 20 therethrough. Furthermore, the end blocks or members 14^b provide relatively wide flat side walls for engagement with the bumping devices. The blocks also provide bumper abutments capable of withstanding severe 25 bumping strains, thus permitting the molds to be operated at a relatively fast rate of speed and rapidly bumped endwise to insure quick and positive separation of the bricks from the walls of the mold sections. 30 The blocks also permit the side members to be secured thereto by four tenons, which insures a strong mold structure.

The width of the blocks 14^b is of special advantage as they are thereby readily adapted 35 for engagement with different types of supporting, guiding and conveying devices, which may or may not be spaced equally apart, without themselves being required to be kept in perfect alinement at the time 40 of delivery to or while being moved from one point to another on the conveying and supporting devices of the apparatus; in other words, the blocks are of a width to provide a sufficient bearing surface to engage with and move on the various supporting parts of the apparatus without danger of disalignment or dislodgment of the blocks therefrom. This form of construction is advantageously employed in connection 45 with gravity conveyers, such as shown at 52, the rollers of which serve to guide as well as support the mold; also in connection with supporting and operating parts which when correlated are not in alinement 50 with each other, as shown in Fig. 6.

The upper surfaces of the blocks 14^b are preferably disposed in the plane of the upper edges of the sides 14^a and partitions 14^c, but for reasons about to be set forth, 60 the blocks 14^b are not as thick as the body portion of the mold 14 is high, that is, their lower surfaces are disposed in a plane slightly above the lower surfaces of the bottoms 14^b, as clearly shown in Figs. 2 65 and 2^a. In practice, it is customary to soak

the molds in water in order to cause the sand to stick to the walls of the molds when passing through the sander. This water soaking operation causes the end members to swell slightly in size, thus increasing their 70 height. Accordingly, when the end members of the mold were made equal in thickness to the height of the side members or body portion of the mold and the latter was moved over the table to a position below 75 the die 13, the table and die would engage with the end members, but as these members had, due to their water soaked condition, become thicker than the body of the mold, they would prevent the die from engaging the body portion of the mold between the end members. As a result a space was formed between the body portion of the mold and the lower surface of the die. When the mold was again moved forward, 80 the scraping edge of the die did not scrape off the material disposed above the plane of the upper surface of the mold; but due to the space between the upper edge or surface of the mold and the scraping edge of 85 the die, a thin layer of material was left on top of the mold, which material had to be scraped off by a separate operation.

In my improved construction of mold, the end blocks 14^b are not as high as the 90 body portion of the mold; accordingly, even when water soaked and their thickness is increased, the end blocks freely move between the base 22 and die 13 and permit engagement of the latter with the entire upper surface of the mold between the end blocks 14^b (as shown in Fig. 5); as a result, when the mold is positioned for filling and filled and is again moved forward, 100 the die will scrape off all material above 105 the upper surface of the mold.

14^e indicates a metallic binding strip extending along the upper edge of each side member 14^a, then around the ends of the side members 14^b and over the bottoms 14^a. 110 14^f indicates similar strips extending along the upper edges of the partitions 14^c. Each end of each strip 14^f is preferably secured to the adjacent strip 14^e by a dove tail joint as shown in Fig. 4. 14^g indicates an upper 115 plate mounted on the upper surface of each block 14^b. The strips 14^e and 14^f and the plates 14^g are preferably made from the same thickness of material so that their upper surfaces will be disposed in the same 120 plane. The strips 14^e and the plates 14^g may be secured to their respective mold parts in any desired manner, as for instance, by counter sunk screws.

14^h indicates a strip extending along the 125 lower edge of each partition. The strips 14^h are preferably secured to the partitions 14^c by rivets 14ⁱ which also secure the strips 14^f to the upper edges of the partitions.

The strips 14^e, 14^f, 14^h and plates 14^g 130

serve to protect the mold, so that it will have long life and certain of the walls of the mold sections will maintain their shape.

5 The strips 14^a and 14^b serve to prevent wearing along certain edges of the mold.

The opposite side edges of each bottom 14^a are preferably inclined inwardly and downwardly to overcome any tendency of the material to clog the vents.

10 To those skilled in the art of making devices of the class described, many alterations in construction and widely differing embodiments and applications of my invention will suggest themselves without departing from the spirit and scope thereof. 15 My disclosures and the description herein are purely illustrative and are not intended to be in any sense limiting.

What I claim is:

20 1. A brick machine mold having at its opposite ends laterally extending members, one surface of each of said members being relatively wide and flat from end to end and adapted to serve as a bearing or supporting surface for the mold.

25 2. A brick machine mold having at its opposite ends laterally extending members, the upper and lower surfaces of each of said members being relatively wide and flat from end to end and adapted to serve as bearing or supporting surfaces for the mold.

30 3. A brick machine mold having at its opposite ends laterally extending members, each said member being of less height than the height of the mold and one surface thereof being flat from end to end and arranged to engage supports for the mold.

35 4. A brick machine mold having at its opposite ends laterally extending members, each of which is of less height than the height of the mold, one surface of each member being flat from end to end and flush with the upper edge of said mold and

arranged to serve as a supporting surface therefor.

40 5. A brick machine mold having at its opposite ends supporting members extending laterally beyond the bottom boards of said mold and provided with upper and lower relatively wide, flat bearing surfaces, 50 the upper surfaces of said laterally extending members being disposed in the plane of the upper edge of the mold and the lower surfaces of said laterally extending members being disposed in a plane between the 55 upper and lower edges of the mold.

6. A brick machine mold having at its opposite ends laterally extending members provided with upper and lower relatively 60 wide, plane surfaces extending from end to end thereof and arranged to serve as bearing surfaces for the mold, one of said plane surfaces of each said member being disposed in a plane between the upper and lower edges of the mold.

65 7. A brick machine mold having at its opposite ends supporting members of substantially rectangular shape in cross section, the upper, lower and outer side surfaces of each said member being flat from edge to 70 edge.

8. A brick machine mold having at its opposite ends supporting members each of substantially rectangular shape in cross section and of less height than said mold, the 75 upper, lower and outer side surfaces of each said member being flat from edge to edge.

9. A brick machine mold having supporting members secured thereto at its opposite ends, the outer side wall of each said end 80 member being flat and of the same height from end to end for engagement with the bumping devices of the brick machine.

In testimony whereof, I have subscribed my name.

HENRY W. B. GRAHAM.
